Matthew W. Mitchell(57) **CLAIM**

The ornamental design for a leg accessory garment, as shown and described.

DESCRIPTION

FIG. 1 is a front isometric view of the leg accessory garment showing my new design;

FIG. 2 is a front view thereof;

FIG. 3 is a left side plan view thereof;

FIG. 4 is a right side plan view thereof;

FIG. 5 is a top plan view thereof; and,

FIG. 6 is a bottom plan view thereof.

The dash lines shown in the drawings indicate stitching and form part of the claimed design.
